US0D1073113S

(12) **United States Design Patent** (10) **Patent No.:** **US D1,073,113 S**
(45) **Date of Patent:** **** Apr. 29, 2025**

(54) **MEDICAL DEVICE CONTROLLER**

(71) Applicant: **TIMOTION TECHNOLOGY CO., LTD.**, New Taipei (TW)

(72) Inventor: **Yu-Chen Wu**, New Taipei (TW)

(73) Assignee: **TIMOTION TECHNOLOGY CO., LTD.**, New Taipei (TW)

(**) Term: **15 Years**

(21) Appl. No.: **29/916,421**

(22) Filed: **Nov. 10, 2023**

(51) **LOC (15) Cl.** **24-02**

(52) **U.S. Cl.**

USPC **D24/185**; D13/162

(57) **CLAIM**

The ornamental design for a medical device controller as shown and described.

DESCRIPTION

FIG. 1 is a perspective view of a medical device controller showing my new design;

FIG. 2 is a front view thereof;

FIG. 3 is a rear view thereof;

FIG. 4 is a left side view thereof;

FIG. 5 is a right-side view thereof;

FIG. 6 is a top view thereof;

FIG. 7 is a bottom view thereof; and

FIG. 8 is second perspective view; and,

FIG. 9 is third perspective view showing the medical device controller.

The broken lines shown in the figures are for the purpose of illustrating portions of the medical device controller and form no part of the claimed design.

1 Claim, 9 Drawing Sheets
